(57) **CLAIM**

The ornamental design for a high performance multi-purpose frigate, as shown and described.

DESCRIPTION

FIG. 1 is a front perspective view of a high performance multipurpose frigate showing our new design, the broken lines are for illustrative purposes only and form no part of the claimed design;

FIG. 2 is a front elevational view thereof;

FIG. 3 is a rear elevational view thereof;

FIG. 4 is a side elevational view thereof, the opposite side view being a mirror image of that shown;

FIG. 5 is a top plan view thereof; and,

FIG. 6 is a bottom plan view thereof.
